UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

CASING FOR LAMP-SOCKETS AND THE LIKE.

1,267,875.

Specification of Letters Patent. Patented May 28, 1918.

Application filed April 8, 1912. Serial No. 689,287.

To all whom it may concern:

Be it known that I, CHARLES J. KLEIN, a citizen of the United States, residing at Milwaukee, in the county of Milwaukee and State of Wisconsin, have invented new and useful Improvements in Casings for Lamp-Sockets and the like, of which the following is a full, clear, concise, and exact description, reference being had to the accompanying drawing, forming a part of this specification.

My invention relates to incandescent lamp sockets and the like, and more particularly to the non-current-carrying parts of such devices.

It has among its objects to provide a casing for electrical devices wherein a portion of the device contained within the casing coöperates with the parts of the casing to lock the same against relative movement. A further object of my invention is to provide an electric lamp socket or switch casing wherein the switch mechanism may be adjusted to and securely locked in any one of a plurality of angular positions with respect to the fixed part of its inclosing casing. Other objects and advantages of my improved construction will hereinafter appear.

In order to more clearly and fully disclose my invention, I have illustrated it as applied to a lamp socket. It is to be understood however that the form shown herein is susceptible of modification.

Figure 1 is a perspective view of an assembled lamp socket.

Fig. 2 is a central longitudinal sectional view of the same.

Fig. 3 is a side elevation of the shell.

The device contained within the casing is shown herein to be a switch mechanism of the pull chain type. This switch mechanism is inclosed with a base 1 and housed within a lamp shell 2 having a cap 3.

I provide this base with a laterally extending projection 4 which extends through any suitable opening 5 in the side of the shell 2 and coöperates with the parts of the casing to lock the same securely against relative rotation, and at the same time serves to lock the switch mechanism securely in position within the casing.

In order that the cap 3 may coöperate with this projection and the shell 2 to lock the parts together, the lower edge of the cap rim 6 is provided with a plurality of

cut-away portions 7 which fit over the projection 4 as shown in Fig. 1. In a preferred form these cut-away portions are in the form of scallops which extend entirely around the periphery of the rim 6 so that the device contained within the casing may be adjusted in any one of a large number of different angular positions. It is obvious, however, that the shape of these cut-away portions may be modified to correspond to the shape of the projecting portion of the device contained within the casing.

In constructions wherein the base is formed in two parts this projection is likewise preferably formed in two parts. It is further to be noted that this projection serves the additional functions of acting as a guide for the operating member and as a means for insulating the same. For instance in the construction shown the projection is provided with a central opening 8 through which the pull chain 9 passes to the switch mechanism.

The shell 2 and cap 3 are secured together by suitable means. In the construction shown I provide a catch 10 on the shell 2 which is adapted to snap over an annular shoulder 11 on the cap when the parts are brought together, and thus prevent accidental longitudinal separation of the same. When it is desired to separate the parts longitudinally they may be readily disconnected by compressing the shell at a point beneath the catch 10 to cause the latter to disengage from the shoulder 11. Through the provision of this annular shoulder 11 the shell and cap may obviously be connected when in any angular position with respect to each other.

When it is desired to connect the two parts of the casing, the shell 2 containing the switch mechanism may be readily connected to the cap 2 by simply bringing the parts together into the position shown in Fig. 1, the catch 10 on the shell automatically snapping over the shoulder 11 on the cap to hold the parts together. In this position the projection 4 is securely clamped between the cap and shell and so coöperates with the parts of the same that the relative rotation of the latter is prevented. Further, the switch mechanism is securely locked within the casing and may occupy any one of a plurality of different angular positions with respect thereto. It is thus seen that the por-

tion of the device contained within the casing which projects through the shell serves not only as a means for locking the parts of the inclosing casing against relative rotation, but at the same time serves to lock the device securely in position within the casing.

It is to be noted that my invention is adapted to use in connection with switch mechanisms of different types and that it may be readily used with key or push button operated switch mechanisms if desired, or in any relation wherein a portion of the device contained within the casing projects therefrom. Further if desired the cap and shell may be of different construction from that shown and may be attached to each other by other suitable means.

While in this application I have specifically described one form of my invention this construction shown herein may be modified without departing from its spirit and I accordingly do not restrict myself to the precise construction shown for purposes of illustration.

What I claim as new and desire to secure by Letters Patent is as follows:—

1. In combination, a cap, a shell, snap means for releasably locking the same against longitudinal separation, and a base housed in said shell and having a portion engaging the latter for supporting said base therein and also engaging said cap and shell for locking the same against relative rotation.

2. In combination, a cap, a shell telescoping therewith, said cap and shell having means for locking the same against separation in any one of a plurality of rotary relations, and an insulating base housed within said cap and shell and having an integral part engaging both of the same when telescoped in any of a plurality of rotary relations to lock the same against relative rotation.

3. In combination, a cap, a shell telescoping therewith, one of said parts having a plurality of circumferential shoulders and the other having shoulders spaced therefrom, and a device contained in said shell and having a portion engaging a shoulder thereof and a shoulder of said cap for locking the same against relative rotation in any telescoped rotary relation.

4. In combination, a cap, a shell, a switch supporting device housed therein and locking said cap and shell against relative ro-

tary movement, and independently operative means to releasably lock said cap and shell against separation.

5. In combination, a cap, a shell, a device removably housed therein and locking said cap and shell against relative rotary movement in any one of a plurality of rotary positions, and independently operative means to releasably lock said cap and shell against separation.

6. In combination, a cap having a serrated margin, a shell telescopically engaged therewith and a radial projection carried by said shell engaging the sides of one of the serrations of said cap to lock said cap and shell against relative rotation.

7. In combination, a cap and shell adapted to telescopically unite, said cap having a plurality of notches about its lower edge, and a radial projection carried by said shell adapted to enter any one of said notches to lock said cap and shell against relative rotation.

8. In combination, a cap and shell adapted to telescopically unite, said cap having a plurality of notches about its lower edge, and a cooperating projection extending outwardly from the wall of said shell to lock said cap and shell against relative rotation, said notches being peaked whereby said projection will be guided thereby into locking position when the parts are united.

9. In combination, a shell, a cap having a scalloped lower rim fitting over the upper end of said shell, a base housed in said shell and having a portion protruding therefrom, said portion being received in the scalloped rim of said cap to lock the shell and cap against relative rotation and means to lock the same against axial separation.

10. In combination, a shell, a cap therefor having a scalloped rim, a switch mechanism housed in said shell, a base having a guiding member for a portion of the switch mechanism protruding from the shell and received in the scalloped rim of said cap to lock said base in position in said shell and to lock said cap and shell against relative rotation and means to lock the same against axial separation.

In witness whereof, I have hereunto subscribed my name in the presence of two witnesses.

CHARLES J. KLEIN.
